UNITED STATES PATENT OFFICE.

JULIUS B. FENSTERWALD, OF BALTIMORE, MARYLAND.

OVERCOAT.

1,098,665.

Specification of Letters Patent.

Patented June 2, 1914.

Application filed September 5, 1911. Serial No. 647,597.

To all whom it may concern:

Be it known that I, JULIUS B. FENSTERWALD, a citizen of the United States, residing at Baltimore, in the State of Maryland, have invented a new and useful Overcoat, of which the following is a specification:

The present invention appertains generally to overcoats, and relates more particularly to novel and improved collars therefor.

It is the object of the present invention to provide an overcoat having a novel and improved collar and lapels, which will permit the coat to be employed as a dress coat, or as a military or storm coat.

Another object of the present invention is to provide an overcoat with a collar and lapels of the nature indicated, in order that the end portions of the collar and lapels may be shifted upwardly and downwardly to convert the coat from a dress style, to a military or storm style and vice versa, without affecting the "break" or back of the collar.

With the foregoing general objects outlined, and with other objects in view, as will be apparent as the nature of the invention is better understood, the present invention resides in the combination and arrangement of parts and in the details of construction hereinafter described and claimed, it being understood that changes in the precise embodiment of the invention herein disclosed can be made within the scope of what is claimed without departing from the spirit of the invention.

The invention has been illustrated in its preferred embodiment in the accompanying drawings, wherein:

Figure 1 is a front elevation of an overcoat constructed in accordance with the present invention, the end portions of the collar being raised, and the lapels being overlapped in the military or storm style. Fig. 2 is a similar view showing the lapels shifted upward, but extended away from each other, to provide a contracted gorge. Fig. 3 is a similar view illustrating the end portions of the collar and lapels shifted downwardly to form a dress coat. Fig. 4 is a front elevation of the collar on an enlarged scale, the tips or corners of the collar being turned upward to disclose the fastening means for attaching the ends of the collar together when they are raised. Fig. 5 is a plan view of the collar and lapels prior to folding,

parts being broken away. Fig. 6 is a sectional detail on the line 6—6 of Fig. 1. Fig. 7 is an enlarged plan view of one end portion of the collar, illustrating the flexible non-creasable lining therefor.

In carrying out the invention, reference being had in detail to the drawings, there is provided an ordinary body 1 for the overcoat, which is provided with the inner and outer lapels 2 and 3, respectively, the outer lapel being provided with a button hole 4, while the body of the overcoat is provided with a button 5 normally underlying the inner lapels 2, in order that when the lapels are overlapped, as illustrated in Fig. 1, the button 5 may be engaged through the button hole 4 to hold the lapels in such condition. By this means, the lapels, may be held in overlapped or crossed position, when the coat is adjusted for the military or storm style.

The body 1 of the overcoat is provided with a laydown collar 6 which is preferably of a number of plies, in order that the collar will be relatively stiff, the end portions or flaps of the collar 6 being designated by the respective numerals 7 and 8.

The back portion 9 of the collar intermediate its ends is of usual height, and is adapted to remain so at either adjustment of the collar and lapels, in order that the "break" between the points *f*—*f* at the back of the collar will remain unchanged under all conditions. Ordinarily, the lapels lie flatly on the breast of the coat, to provide a dress coat, the upper ends *a* of the lapels being adapted to abut against the ends or extremities *b* of the collar 6, and the slits between the ends of the collar and the lapels terminating short of the fold lines when the coat is in this condition, as will be clearly apparent by reference to Fig. 3.

One of the cardinal or salient features of the present invention resides in the provision of freely flexible portions 7' and 8' between the end portions or flaps 7 and 8 of the collar, and the body of the overcoat, the folds between the body of the overcoat, and the end portions of the collar and lapels being freely flexible between the lines *F* and *F'*. Thus the portions 2' and 3' between the respective lapels 2 and 3 and the body of the overcoat must naturally be flexible to permit the folds to be shifted. Thus, when the lapels and end portions of the collar are shifted downwardly, as seen in Fig. 3, to

form a dress coat, the folds will extend along the lines F, while the folds of the lapels when they are shifted upward as seen in Fig. 2, will extend along the lines F'. Similarly, when the end portions of the collar are laid flat upon the breast as seen in Fig. 3, the flexible portions 7' and 8' will be exposed and will in reality form portions of the flaps 7 and 8. When the lapels are shifted downwardly, as seen in Fig. 3, the flexible portions 2' and 3' will also provide portions of the lapels, while when the ends of the collar and lapels are shifted upwardly as seen in Fig. 2, the flexible portions 7' and 8' will pass in back of the end portions of the collar, and the flexible portions 2' and 3' will pass in back of the lapels. It is to be observed that the shifting of the end portions of the collar and lapels from one position to the other, will not affect the rear portions or back of the collar, or will not alter the "break". A pair of hooks 11-12 are carried by the inner side of the flap 7, and corresponding eyes 13-14 are carried by the inner side of the flap 8, in order that the hooks and eyes or fastening members may be interengaged when the said flaps or end portions of the collar are shifted upwardly to form a storm or military coat, it being observed that the end portions of the collar are adapted to abut when they are shifted upwardly, so as to snugly inclose the throat of the wearer, and so as to fit snugly under the chin. An eye 15 is carried by the inner side of the lapel 2 adjoining its upper end *a* while a hook 16 is carried by the inner side of the lapel 3 adjoining its upper end *a*, the fastening members 15 and 16 being engageable with the fastening members 12 and 14, respectively, of the flaps or end portions of the collar when the overcoat is adjusted as seen in Fig. 3, in order that the adjoining or meeting ends of the collar and lapels abut. In this manner, the ends of the collar and lapels, may be attached together when the overcoat is set to dress style. The end portions or flaps of the collar and lapels are thus conveniently held flatly against the breast to provide a neat and dressy effect.

The collar 6 embodies the facing 17 and the backing 20, between which there is secured a reinforcement 18, which is preferably coextensive with the facing and backing. The flaps 7 and 8 are provided with flat flexible linings or pieces of hair cloth 19 or the like, which extend into the freely flexible portions 7' and 8', the linings 19 being freely flexible and not readily creasable in order that the portions 8' and 7' may be easily flexed or folded without becoming pressed in one position.

The linings 19 are preferably constructed of haircloth, and are four-sided as seen in Fig. 7. Certain edges of the linings 19 ex-

tend directly along the normal fold lines of the flaps or end portions of the collar when the same are in dress position, the opposite edges of the linings extending along the edges of the collar. Certain of the other edges of the linings 19 extend along the ends of the collar, the linings being relatively short and the edges thereof remote from the ends of the collar terminating intermediate the ends of the collar and the break. The linings tend to remain flat, to hold the end portions of the collar flat upon the body of the coat, the linings, however, being flexible to enable the end portions of the collar to be shifted upwardly to military position, whereby the linings will be doubled. Thus, when the end portions of the collar are shifted upwardly to a military position, and when the hooks and eyes attached to the ends of the collar are interengaged, the ends of the collar will be held together, and furthermore, the linings will be maintained in doubled positions, the inner portions of the linings pressing inwardly against the neck of the wearer. The ends of the collar being attached by the hooks and eyes, will hold the collar in military position, against the tension of the linings which tend to unfold or flatten the flaps or end portions of the collar so as to assume a normal or dress position. It will also be evident that due to the formation of the slits between the ends of the collar and lapels, when the ends of the collar are shifted upwardly, the lapels will be correspondingly raised or elevated, and held in such condition, when the ends of the collar are attached.

In use, when a dress coat is desired, the end portions or flaps of the collar or lapels are shifted downwardly, and the respective fastening members of the collar and lapels are attached to hold the end portions of the collar and lapels flat upon the breast. When the collar and lapels are thus adjusted, a relatively large gorge will be provided. To convert the overcoat into a storm or military coat, it is simply necessary to detach the ends of the collar and lapels, which will permit the ends of the collar and lapels to be shifted upwardly as seen in Fig. 2, the ends of the collar abutting against each other and the lapels contracting the gorge, so that the fastening members of the collar may then be engaged so as to hold the collar in position. It is to be observed that when the ends of the collar and lapels are shifted upwardly, the respective flexible portions or folds will pass in back of the ends of the collar and lapels so that the lapels may be overlapped as seen in Fig. 1, or may be left open as seen in Fig. 2, whichever is desirable.

Attention is again directed to the fact that when the ends of the collar and lapels

are manipulated or adjusted as specified, the back or rear portion of the collar, as well as the "break," will not be in any manner affected, which is desirable.

5 The present collar is comfortable and neat, the same not being accompanied by any bunglesome or cumbersome plaits, double folds or the like.

What is claimed is:

- 10 A coat having a lay down collar and lapels, the break at the back of the coat being stationary, the adjoining ends of the collar and lapels being separated by slits terminating short of the normal fold lines 15 of the lapels and end portions of the collar when they are in dress position, the folds between the body and the lapels and end portions of the collar being flexible to permit the lapels and end portions of the collar 20 to be shifted upwardly to military position, a flat four-sided haircloth lining for each end portion of the collar, certain edges of the lining extending directly along the normal fold lines of the end portions of the 25 collar when the same are in dress position, the opposite edges of the linings extending

along the edges of the collar, certain of the other edges of the linings extending along the ends of the collar, the linings being relatively short and those edges thereof remote 30 from the ends of the collar terminating intermediate the ends of the collar and the break, the linings tending to remain flat to hold the end portions of the collar flat upon the body of the coat, and being flexible to 35 enable the end portions of the collar to be shifted upward to military position whereby by the linings will be doubled, and interengageable members carried by the ends of the collar and arranged to hold the ends 40 of the collar together when they are arranged in military position, whereby the linings will be maintained in doubled condition and in order that the inner portions of the linings will press inwardly. 45

In testimony that I claim the foregoing as my own, I have hereto affixed my signature in the presence of two witnesses.

JULIUS B. FENSTERWALD.
